(57) **CLAIM**

The ornamental design for a hair colorant root touch-up clip, as shown and described.

DESCRIPTION

FIG. 1 is a top, front, right perspective view of a hair colorant root touch-up clip in a closed configuration, according to the present invention.

FIG. 2 is a right view of the hair colorant root touch-up clip of FIG. 1.

FIG. 3 is a left view of the hair colorant root touch-up clip of FIG. 1.

FIG. 4 is a top view of the hair colorant root touch-up clip of FIG. 1.

FIG. 5 is a bottom view of the hair colorant root touch-up clip of FIG. 1.

FIG. 6 is a front view of the hair colorant root touch-up clip of FIG. 1.

FIG. 7 is a rear view of the hair colorant root touch-up clip of FIG. 1; and,

FIG. 8 is a top, front, right perspective view of the hair colorant root touch-up clip of FIG. 1, in an open configuration.
